US0D1059386S

(12) **United States Design Patent** (10) **Patent No.:** **US D1,059,386 S**
Balamuthusamy et al. (45) **Date of Patent:** **** Jan. 28, 2025**

(54) **DISPLAY SCREEN WITH GRAPHICAL USER INTERFACE**

(71) Applicant: **Optmycare, Inc.**, Dallas, TX (US)

(72) Inventors: **Saravanan Balamuthusamy**, South Lake, TX (US); **Antony Pfaffle**, Bronx, NY (US)

(73) Assignee: **Optmycare, Inc.**, Dallas, TX (US)

(**) Term: **15 Years**

(21) Appl. No.: **29/856,288**

(22) Filed: **Oct. 12, 2022**

(51) **LOC (15) Cl.** **14-04**

(52) **U.S. Cl.**

USPC **D14/485**

(57) **CLAIM**

The ornamental design for a display screen with graphical user interface substantially as shown and described.

DESCRIPTION

The FIGURE is a front view of a display screen with graphical user interface.

The broken lines showing the display screen form no part of the claimed design. The remaining broken lines showing text and portions of the graphical user interface form no part of the claimed design.

1 Claim, 1 Drawing Sheet
